UNITED STATES PATENT OFFICE

158,061

CHILDREN'S PLAY VEHICLE

Louise M. Jones Foulke, Brooklyn, N. Y.

Application May 23, 1947, Serial No. 139,240

Term of patent 14 years

(Cl. D34—15)

To all whom it may concern:

Be it known that I, Louise M. Jones Foulke, a citizen of the United States, residing at Brooklyn, in the county of Kings, in the State of New York, have invented a new, original, and ornamental Design for a Children's Play Vehicle, of which the following is a specification, reference being had to the accompanying drawing, forming a part hereof.

Fig. 1 is a plan view of a children's play vehicle, showing my new design; Fig. 2 is a side elevational view of the same, and Fig. 3 is a rear elevational view of the same.

I claim:

The ornamental design for a children's play vehicle, as shown.

LOUISE M. JONES FOULKE.
